Primary Examiner — Austin Murphy(74) *Attorney, Agent, or Firm* — Ladas & Parry LLP(57) **CLAIM**

We claim the ornamental design for the kiosk, as shown and described.

DESCRIPTION

FIG. 1 is a front perspective view a first embodiment of a kiosk showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is an exploded view thereof;

FIG. 9 is a front perspective view of a second embodiment of the design without the lowest unit; and,

FIG. 10 is a front perspective view of a third embodiment of the design which may be placed against a wall.

The broken lines in the figures represent unclaimed portions of the kiosk and form no part of the claimed design.
